THERMOSTAT HOUSING

William A. Ray, North Hollywood, and Harold W. Vaughn, South Pasadena, Calif., assignors to General Controls Co., Glendale, Calif., a corporation of California

Application February 21, 1955, Serial No. 34,596

Term of patent 14 years

(Cl. D52—7)

Fig. 1

Fig. 2

Fig. 3

Figure 1 is a perspective view of a thermostat housing embodying our new design; and

Figures 2 and 3 are views thereof, to reduced scale, taken from the top and from the bottom, respectively.

The opposite side of the thermostat housing is substantially the same in appearance as the side shown.

We claim:

The ornamental design for a thermostat housing, substantially as shown and described.
